(Cl. D14—18)

—FIG. 1

—FIG. 3

—FIG. 4

—FIG. 2

FIG. 1 is a top plan view of a cap for automobile gasoline tanks showing my new design.

FIG. 2 is a bottom plan view thereof.

FIG. 3 is a side elevational view thereof as shown in FIG. 1;

FIG. 4 is a side elevational view rotated 90° from the position shown in FIG. 3;

FIG. 5 is a top plan view of a modified form of the cap shown in FIG. 1;

FIG. 6 is a bottom plan view of FIG. 5;

FIG. 7 is a side elevational view of FIG. 5; and

FIG. 8 is a side elevational view rotated 90° from the position shown in FIG. 7.

The dominant features of my design reside in the portions shown by means of full lines in the drawings.

I claim:

The ornamental design for a cap for automobile gasoline tanks or the like, substantially as shown and described.
